UNITED STATES PATENT OFFICE.

JULIUS WÜSTENHÖFER, OF DORTMUND, GERMANY.

SAFETY CATCH FOR ELEVATORS, LIFTS, OR THE LIKE.

Application filed September 23, 1926, Serial No. 137,196, and in Germany December 27, 1924.

- Safety catches for elevators, lifts or the like have become known, in which the braking of the dropping elevator-cage is produced by doing cutting work. With this object in view tools are arranged on the cage which, when the hoisting rope breaks, are automatically brought into operative position whereupon they execute their cutting work on the cage-guides.
- 10 Safety-catches of this type present the serious inconvenience that the guide bars, i. e. very important constituents of the elevators and of the shaft timbering, are put under stress. If these catches work under 15 unfavorable conditions, i. e. if a fully loaded cage drops at a maximum speed, the guide bars, on which the whole cutting work is done, are weakened and damaged in such a manner, that they will have to be renewed.
- 20 In connection with safety-catches which are provided with dentate or toothed catch claws or braking rollers, it has been proposed to arrange special boardings or brake-beams, separate from the guide bars, with which 25 boardings or brake-beams the gripping elements co-operate. These means are however of no advantage because the necessary repairs have merely been transferred from the guide bars to other elements of the shaft 30 which must be also of very strong construction, so that the work of the elevator is disturbed in the same manner as before if the catching device has functioned.
- The present invention has for its object 35 to avoid these inconveniences essentially by making the tools, arranged on the cage and getting into the working position upon the breaking of the hoisting rope, cooperate with special work-pieces or elements which are 40 arranged on the shaft in continuous succession but removable so that the tools will cut off these pieces of material by cutting, planing, chipping, grooving, shearing or in a similar manner. The invention abandons 45 completely the braking work on the guide bars or on special boardings arranged in the shaft or on brake-beams and utilizes special work-pieces for consuming the energy of fall of the cage by the work of tools. These 50 work pieces may be fixed on the guide beams. After breaking of the hoisting rope only a certain number of these work pieces are damaged, while the guide beams remain intact. As soon as the rope has been re-at- 55 tached the elevator can proceed its work whilst the damaged work pieces are renewed at convenient occasion.
- From the special work pieces arranged in accordance with the invention the great advantage results that they exclusively serve 60 for consuming work, no other elements of construction being used for this purpose. By giving to these work pieces or elements a suitable shape they can be perfectly adapted to the tools mounted on the cage so that, 65 on the one hand, a secure engaging of the tools into the work elements is ensured and, on the other hand, the work proceeds smoothly, so as to continuously consume the energy of fall, and in such a manner that 70 neither important parts of the elevator are injured nor clogging of the tools occurs. With this object in view the work piece or elements are preferably made of such dimensions that 75 by each element or by a group of work elements arranged at the same height only a certain portion of the total braking work is done, so that a number of successive work elements will be utilized till the total effect, i. e. the stopping of the cage, has been attained. 80 Every individual work element is, in accordance with the invention, thickened in wedge-shape from above downward. In this manner not only the penetrating of the cutting edges of the tools into the material of the 85 work element is considerably facilitated, so that no idle slipping can occur, but the effect is further obtained that the shaping or planing knives have to detach from each work element a cutting or chip of a thickness 90 which increases from above to below. On each work element the energy of fall of the cage encounters, therefore, an increasing resistance. When, at the moment of breaking of the rope, the device begins to operate, 95 the tools, coming in operative position, brake, owing to this shape of the work elements, the cage at first softly and consume then by increasing work a portion of the fall energy. On the next following work 100 element the tools again begin to act softly to consume at increasing thickness of the cutting another portion of the fall energy, and so forth, until the cage has been stopped. In this manner it is possible to catch the falling cage almost without shock and to stop the same, on a longer braking travel, in a 105 sliding motion which becomes gradually slower, without appreciable shocks.

The stepwise braking of the cage as de- 110

scribed above may be further improved by arranging in one row of work elements successively work elements consisting of material of different hardness (wood or metal), so that the consumption of energy is increased by successively cutting off work elements of different hardness. As, evidently, the energy consuming rows of work elements are arranged on either side of the cage in the shaft the wedge-shaped work elements in the two rows might be displaced the one with regard to the other so that the beginning or end of one work element in one row is situated at the same height as the center of a work element in the other row. Thus the stepwise increasing braking action is preserved for each row so that the effect onto the whole cage remains uniform.

An embodiment of the invention is shown, 20 by way of example, on the accompanying drawing, in which

Fig. 1 shows a part of the improved safety catch in side elevation.

Figs. 2 to 4 illustrate different shapes for 25 the working edges of the planing or cutting tools.

Fig. 5 is a view showing the arrangement of the work elements at both sides of the cage and illustrating a braking action.

30 In Fig. 1 *a* is a cage, *b* the guide bars for the same. On two opposite sides of the cage *a* either at the top or at the bottom or at the top and at the bottom levers *c* are pivotally mounted which have cutting edges 35 *c*¹ at their free ends so that they form planing or cutting tools. The levers *c* are connected by means of counter arms *d* and suitable rods with the hoisting rope so that the tools *c* adopt the position indicated in 40 dot and dash lines when the rope is taut. When the rope breaks the tools are pivoted by the action of springs or the like into the position shown in full lines, the counter arms *d* bearing then against abutments *f* 45 of the cage *a*.

According to the invention work pieces or elements *g* of suitable metal, for instance iron, are fixed in a vertical continuous row on the guide bars *b* of the cage. These 50 work elements *g* adopt with regard to the tools *c* such a position that the tools come into touch with the work elements *g* as soon as the tools, owing to the breaking of the rope, are turned into the operative position. 55 The tools act then by a planing or chopping action upon the work elements *g*, i. e. they cut off from the same cuttings or chips *g*² of certain thickness, whereby the fall energy of the cage is gradually consumed so that 60 the cage is stopped.

The work elements *g* are preferably, on their sides facing the tools, thickened in wedge-shape from above downwards, wherefrom results that the cuttings to be cut off 65 each work element get gradually thicker

towards the bottom end of the work element. In this manner each work element opposes to the tool cutting into it a resistance which increases from above to below.

It is further advisable to use work elements which have, on the side facing the tools, undulations extending transversely to the direction of movement of the cage, as shown on the work element *g*¹, so that the work elements present permanently a secure 75 contacting surface to the tools in operative position.

The planing or cutting tools may have either a continuous working edge *c*¹ as shown in Fig. 2, or a working edge *c*² composed of 80 square teeth as shown in Fig. 3, or composed of pointed teeth *c*³ as shown in Fig. 4.

The work pieces or elements *g* are removably fixed on the guide bars *b* so that the work elements which have been damaged 85 by the catching of a cage can be rapidly replaced by fresh elements.

In some lifts or elevators it is usual to securely hold the cage in the prescribed height with regard to the junction line at 90 the loading or charging places by means of bolts or the like pushed under the cage. As at this occasion slackening of the rope occurs frequently, whereby the tools *c* would be turned partly or completely into the 95 working position, it is advisable to omit certain work elements *g* at the loading or charging places.

Many modifications of construction or other embodiments of the invention are evidently possible. 100

I claim:—

1. A device for catching falling cages comprising in combination with the cage and with the guide bars for the cage, tools 105 on the cage and adapted to be brought automatically into the operative position when the rope breaks, and work pieces or elements detachably fixed in a continuous row on said guide bars and designed to be worked upon 110 by said tools.

2. A device for catching falling cages comprising in combination with the cage and with the guide bars for the cage, tools on the cage and adapted to be brought automatically into the operative position when the rope breaks, and work elements detachably fixed in a continuous row on said guide bars and designed to be worked upon by 115 said tools, said work elements being thickened in wedge-shape towards the bottom end on the side facing said tools. 120

3. A device for catching falling cages comprising in combination with the cage and with the guide bars for the cage, tools on the cage and adapted to be brought automatically into the operative position when the rope breaks, and work elements detachably fixed in a continuous row on said guide bars and designed to be worked upon by 125 said tools. 130

tools, said work elements being thickened in wedge-shape towards the bottom end on the side facing said tools, and having on their working surfaces undulations transversely to 5 the direction of travel of said cage.

4. A device for catching falling cages comprising in combination with the cage and with the guide bars for the cage, tools on the cage and adapted to be brought automatically into the operative position when 10 the rope breaks, and work elements detachably fixed in a continuous row on said guide bars and designed to be worked upon by said tools, the upper work elements of each group 15 of successive elements being of softer material and the lower work elements being of harder material.

5. A device for catching falling cages comprising in combination with the cage and 20 with the guide bars for the cage, tools on the cage and adapted to be brought automatically into the operative position when the rope breaks, and work elements detachably fixed in a continuous row on said guide bar 25 and designed to be worked upon by said tools, said work elements being thickened in wedge shape towards the bottom end on the

side facing said tools, the work elements on the guide bar at one side of said cage being displaced with regard to the work elements 30 on the guide bar at the opposite side of said cage so that the lower end of the work elements on one side of the cage stand at the same height as the center of the work elements on the other side of the cage. 35

6. A device for catching falling cages comprising in combination with the cage and with the guide bars for the cage, tools on the cage and adapted to be brought automatically into the operative position when 40 the rope breaks, and work elements detachably fixed in a continuous row on said guide bars and designed to be worked upon by said tools, the work elements on the guide bar at one side of said cage being displaced 45 with regard to the work elements on the guide bar at the opposite side of said cage so that the upper end of the work elements on one side of the cage stand at the same height as the center of the work elements 50 on the other side of the cage.

In testimony whereof I affix my signature.

JULIUS WÜSTENHÖFER.
